CLAIM

The ornamental design for a panty, substantially as shown and described.

DESCRIPTION

FIG. 1 is a front perspective view of the panty.

FIG. 2 is a front view of the panty.

FIG. 3 is a back view of the panty.

FIG. 4 is a left view of the panty.

FIG. 5 is a right view of the panty.

FIG. 6 is a top plan view of the panty.

FIG. 7 is a bottom plan view of the panty; and,

FIG. 8 is another front perspective view of the panty.

The broken lines depicting the human form in FIG. 8 is for environmental purposes only and form no part of the claimed design.
